UNITED STATES PATENT OFFICE.

JOSEPH L. WARE, OF ST. PAUL, MINNESOTA, ASSIGNOR TO WARE GRAIN BINDER ATTACHMENT COMPANY, OF ST. PAUL, MINNESOTA, A CORPORATION.

BINDER-HEAD.

1,106,604.

Specification of Letters Patent. Patented Aug. 11, 1914.

Application filed May 2, 1912. Serial No. 694,669.

To all whom it may concern:

Be it known that I, JOSEPH L. WARE, of St. Paul, Ramsey county, Minnesota, have invented certain new and useful Improvements in Binder-Heads, of which the following is a specification.

My invention relates to means for securing a cord around a bundle of grain, corn, hay, or other material, and is designed as an improvement over a portion of the mechanism shown and described in my pending application filed May 1, 1909, Serial No. 493,325.

My invention consists generally in various constructions and combinations, all as hereinafter described and particularly pointed out in the claims.

In the accompanying drawings forming part of this specification, Figure 1 is a vertical sectional view through a binder with by invention applied thereto, showing the parts in their normal position before the movement of the needle to bind the bundle, Fig. 2 is a similar view showing the position of the parts when the needle has carried the cord around the bundle and the parts are in position to place the clip on the crossed portions of the cord, Fig. 3 is a detail sectional view, showing the operating parts of the binder head in their normal position, Fig. 4 is an end view of the same, Fig. 5 is a view, partially in section, taken on the opposite side of the binder head from the view shown in Fig. 3, Fig. 6 is a vertical sectional view illustrating the mechanism for feeding the ribbon, Fig. 7 is a horizontal sectional view showing the position assumed by the parts preparatory to the operation of folding the clip around the cord, Fig. 8 is a detail view, partially in section, showing the position of the parts when the folding operation has been completed, Fig. 9 is a detail view of one of the jaws, Fig. 10 is a detail view of the cord severing knife, Fig. 11 is a similar view, showing the operation of the combined severing knife and cord holder, Figs. 12 and 13 illustrate the manner of placing the clip on the cord.

In the drawing, 2 represents the deck of a binder, 3 the needle, 3' a packer arm, the operation of the needle and the packer arms, being controlled by the trip lever 4 operated through mechanism at the opposite side of

the deck in the usual way on machines of this type.

5 represents the drive shaft, on which the knotter head usually employed with a binder is mounted. The frame 6 of the binder has a hub 7 that is adapted to slip on to the shaft 5, and on this frame the clip forming and folding mechanism is mounted. A disk 8 is secured on the shaft 5 and provided with cam surfaces which I will designate by reference numerals 9 and 10. A plate 11 is secured to one side of the disk and projects radially thereon toward its periphery. A lever 12 is pivoted at 13 on the hub 7 and is provided with a projecting arm 14 having anti-friction rollers 15 and 16 mounted thereon and spaced apart sufficiently to receive the edge of the disk 8 so that in the revolution of the disk the lever 12 will be oscillated back and forth.

A plunger 17 is arranged to slide horizontally between a fixed jaw 18 provided with a longitudinal guide-way 19 and an oscillating knife 20 which has a longitudinal groove 21 in its lower edge to receive the upper edge of said plunger. A guide plate 22 is also provided above the rear portion of the sliding plunger. The plunger is operated by a rod 23 which connects it with the lower end of the lever 12. The plunger has a face 24 at its forward end adapted to engage the clips, as will herein-after appear, and a U-shaped recess 25, the walls of which operate to fold the clip around the crossed cords. The knife 20 has a cutting edge 26 near a slot 27 through which the metallic ribbon 28 is fed.

The mechanism which I prefer to employ for this feeding operation comprises a lower roll 29, an upper roll 30 having a gear connection 31 with the lower roll, said lower roll being pivoted at 32 and provided with a lever 33 and a spring 34 bearing on said lever and holding the roll 29 in contact with the roll 30 with a yielding pressure. The roll 30 is journaled in a wall 35, while the roll 29 is free to oscillate on its pivotal support. These rolls are preferably arranged within a chamber 36 having a door 37 leading thereto and in the upper part of this chamber a lever 38 is mounted, having one end adapted to bear on the knife 20 and provided with a dog 39 at its other end which

engages the teeth of the roller 30 and is held in contact therewith by a spring 40. A spring 41 holds the lever 38 in yielding contact with the upper edge of the knife 20. This knife is mounted on a shaft 42 carrying a fork 43 that is adapted to straddle the disk 8 and has anti-friction rollers 44 mounted thereon. In the revolution of the disk this fork will be oscillated to rock the shaft 42 and swing the knife 20 vertically to cut the clips from the ribbon 28. The upward movement of this knife will tilt the lever 38, revolve the rolls to feed the ribbon between them and on the downward movement of the knife the spring 41 will lift the dog 39 so that it will again catch the teeth of the upper roll to feed the ribbon on the up-stroke of the knife. The plate 11, during the depression of the knife 20, bears on one of the rollers 44 and holds the knife in its depressed position so that it forms a portion of the guide-way for the plunger during the operation of passing the clip around the cord.

At the forward end of the stationary jaw is a curved face 45 and opposite this jaw is a movable jaw 46, also having a curved face 47, between which and the face 45 the cord is gripped during the operation of placing the clip thereon. The jaw 46 is mounted on a lever 48 pivoted at 49 and having an anti-friction roller 50 that is engaged by the cam surface 10 on the disk 8 and rocked at a predetermined point in the operation of the mechanism to move the jaw 46 forward to grip the crossed portions of the cord and hold them firmly during the operation of folding the clip around the cord. (See Fig. 8.) The lever 48 has a part between the pivot 49 and the roller 50 that is slightly flexible to compensate for any variation in the thickness of the cord that is gripped between the movable and stationary jaws. This lever also has a spring 48' (see Fig. 3) which normally tends to hold the movable jaw in its retracted position. The jaw 46 is preferably composed of plates spaced apart, as indicated in Fig. 9, having grooves or recesses in their edges which are adapted to receive the end of the clip and guide it around the crossed portions of the cord, and each plate has a projecting toe portion operating to guide the crossed portions of the cord against the curved face 47 and cooperate with the fixed jaw to hold the portions of the cord securely while the clip is being clamped thereon.

At the lower end of the jaw 46 is a stud 51 which enters a slot 52 in a disk 53 pivoted at 54 on the frame of the binder head. When this jaw 46 moves forward toward the cord, this disk will be rotated to swing in under the cord and lift it up so that the lower end of the movable jaw will pass under the cord 65 and guide it into the curved faces of the

jaws. Backward movement of the disk 53 is limited by a stop 55. I also prefer to provide a spring 56 and a rod 57 pivotally connected with the disk 53, so that when the disk is swung across the throat of the binder head the spring 56 will be put under tension to return the disk to its normal position. The disk 53, in addition to its function of raising and supporting the cord, also clears the throat of any straw or foreign matter 75 that may have collected therein.

Near the movable jaw is a combined cord holder and knife, consisting of a stationary cutter 58 and a sliding blade 59 having a recess 60 therein, the outer wall of said recess 80 being provided with a cutting edge 61 and a blunt or gripping edge 61'. This blade is normally held in its retracted position by a spring 62 and is projected preferably by means of a lever 63 pivoted at 64 on the frame of the binder-head and having one end projecting into a cam groove 65 on the shaft 5. The stationary cutter 58 has a cutting edge 66 which cooperates with the cutting edge 61 of the movable blade to sever 90 the cord which is laid in the path of the cutting edge on the return stroke of the needle, the blunt or rounded portion of the blade being arranged in connection with a suitable means, such as the spring 67, to first grip the cord before the cutting edge 66 engages and severs it to release the newly bound bundle. When this has been done, the bound bundle may be discharged from the machine, while one end of the cord is 100 gripped in the holder preparatory to the formation of another bundle. The tension of the spring 67 may be increased or decreased by the adjustment of the set screw 68.

In the operation of the mechanism, the 105 grain will be delivered to the binder-deck and packed in the usual way by the packer arms and at a predetermined time the needle will carry up the cord and lay it across the end portion that is gripped by the cord 110 holder. When this has been done, the movable jaw will be actuated and will rotate the disk 53 to raise the cord and clear the throat and cooperate with the stationary jaw to grip firmly the crossed portions of the 115 cord. The clip having been severed by the operation of the knife 20, will be moved endwise by the plunger 17 and folded around the cord, one end lapping by the other and pinched by the final movement of the 120 plunger, so that when the jaws are separated the clip will be squeezed securely on the cord, as indicated in Fig. 13. On the return stroke of the needle the cord will be laid in the recess 60 and the gripping and 125 severing operation performed in the manner described.

I have shown my improvement in binder-heads applied to a harvester for binding bundles of grain, but it is evident that a 130

considerable portion of this mechanism could be employed for binding a cord around a bundle of grain, hay, or other material which it is desirable or customary to put up in bundles or bales.

5 I claim as my invention:—

1. The combination, with a binder deck, of a cord holder, means for packing the grain against the cord, a needle arranged to bring up the loose end of the cord and lay it across that portion held by said holder, a ribbon feeding device including coöperating rolls, an oscillating knife arranged to cut a clip from the ribbon, means for operating

15 said knife, means actuated by the movement of said knife for revolving said rolls to feed the ribbon, and means for bending the clip around the contiguous portions of the cord.

2. In a binder head, a cord holder, means arranged to bring up the loose end of the cord and lay it across that portion held by said holder, a ribbon feeding device including coöperating rolls, an oscillating knife and means for operating the same, a lever 20 having one end yieldingly held in contact with said knife, a dog carried by said lever and adapted to engage and operate said rolls, said lever oscillating with the movement of said knife to impart a rotary movement to said rolls.

3. The combination, with a binder deck, of a cord holder, means for packing the grain against the cord, a needle arranged to bring up the cord and lay it across that portion held by said holder, a ribbon feeding device, including coöperating rolls, a clip severing knife and means for operating the same, a spring pressed lever engaging said knife to be actuated thereby, a dog carried 35 by said lever and adapted to engage and revolve said rolls.

4. In a binder-head, a cord holder, means for bringing together the portions of the cord to be clamped, jaws between which the clamp is formed, a throat being provided contiguous to said jaws and holder in which the portions of the cord to be secured together lie, and means actuated by one of said jaws for clearing said throat preliminary to the clamping operation.

5. In a binder head, a cord holder, means for bringing together the portions of the cord to be clamped, jaws between which the clamp is formed, a throat being provided contiguous to said jaws and holder in which the portions of the cord to be secured together lie, and means actuated by the movement of one of said jaws for clearing said throat preliminary to the clamping operation.

6. In a binder head, a cord holder and means for bringing together the portions of the cord to be clamped, jaws between which the clamp is formed, a throat being provided contiguous to said jaws and holder

and in which the portions of the cord to be secured together lie, and a disk operatively connected with one of said jaws and actuated thereby to clear said throat.

7. In a binder-head, means for bringing together the portions of the cord to be clamped, jaws between which the clamp is formed, a throat being provided contiguous to said jaws, a holder in which the portions of the cord to be secured together lie, and means operating at an angle to the plane of said jaws and actuated thereby for lifting said cord.

8. In a binder head, a cord holder, means for bringing together the portions of the cord to be clamped, jaws between which the clamp is formed, a throat being provided contiguous to said jaws and holder in which the portions of the cord to be secured together lie, a disk disposed beneath one of said jaws and operated thereby and adapted to move across said throat and support the cord therein during the clamping operation.

9. In a binder head, a cord holder, means for bringing together the portions of the cord to be clamped, jaws between which the clamp is formed, a throat being provided contiguous to said jaws and holder and in which the portions of the cord to be secured together lie, a disk horizontally arranged and having a slot therein to receive a pin on one of said jaws whereby, when said jaw is operated, said disk will be moved back and forth across said throat, and a stop for limiting the rotary movement of said disk.

10. In a binder-head, a cord holder comprising relatively reciprocating members having opposing gripping jaws between which the cord is held and located on one side of said members, said members also having severing edges located on the opposite side thereof, said severing members operating to cut the cord between the holder and the bundle while said gripping members grip the free end of the cord so severed.

11. The combination, with a deck, of a cord holder including a movable jaw having a cutting and a gripping edge and means co-operating therewith for successively gripping the cord and severing it, means for packing the material to be bound against the cord, a needle arranged to bring up the loose end of the cord and lay it across that portion held by said holder, means for placing a clip around the crossed portions of the cord, means for opening said holder to release the end of the cord held thereby, the needle on its return movement laying the cord in the open holder, the closing of said holder operating to sever the cord between the holder and said clip and release the bundle and grip one end preparatory to binding another bundle.

12. The combination, with a deck, of a

4

cord holder having means for cutting the cord and means for gripping it, means for packing the material to be bound against the cord, a needle arranged to bring up the loose end of the cord and lay it contiguous to that portion held by said holder, means for placing a clip around the contiguous portions of the cord, means for opening the holder to release the end of the cord gripped thereby, the needle on its return movement laying the cord in the open holder, said holder operating to sever the cord between the holder and said clip and release the bundle and grip one severed end preparatory to binding another bundle.

13. In a binder head, a cord holder hav-

ing means for cutting the cord and means for gripping it, means for opening the holder to release the end of the cord gripped thereby, said cutting means operating to sever the cord between the holder and the bundle, and said gripping means engaging one severed end preparatory to binding another bundle when said cord holder is released by said opening means.

In witness whereof, I have hereunto set my hand this 27th day of April 1912.

JOSEPH L. WARE.
